UNITED STATES PATENT OFFICE.

ELLIOTT E. GEISINGER, OF ROCHESTER, NEW YORK, ASSIGNOR TO THE PFAUDLER COMPANY, OF ROCHESTER, NEW YORK, A CORPORATION OF NEW YORK.

CONTAINER APPARATUS.

Application filed October 20, 1923. Serial No. 669,845.

To all whom it may concern:

Be it known that I, ELLIOTT E. GEISINGER, a citizen of the United States, residing at Rochester, in the county of Monroe and State of New York, have invented certain new and useful Improvements in Container Apparatus; and I do hereby declare the following to be a full, clear, and exact description of the same, reference being had to the accompanying drawings, forming a part of this specification, and to the reference numerals marked thereon.

This invention relates to container apparatus, such, for example, as commonly employed for processing food and other substances, and more particularly to the variety comprising means for circulating fluid over the walls of the container, to control its temperature, one object of the invention being to provide apparatus of this character comprising improved fluid circulating means for supplying the fluid to the container walls in an efficient manner. A further object is to provide such apparatus advantageously constructed to distribute the circulating fluid over the container wall in an unbroken film so that all of the fluid is efficiently utilized and uniform results obtained. Still a further object is to provide apparatus of this variety having fluid circulating means constructed to effectively provide against clogging of the passages by scale, sludge or the like, and in which the parts are accessibly arranged. To these and other ends the invention consists in certain improvements and combinations of parts, all as will be hereinafter more fully described, the novel features being pointed out in the claims at the end of the specification.

40. In the drawings:

Fig. 1 is a top plan view, partly broken away, of a container apparatus embodying the present invention.

Fig. 2 is an enlarged fragmentary sectional view on the line 2^a—2^a in Fig. 1.

Fig. 3 is an enlarged longitudinal sectional view of a portion of a tube means shown in Fig. 2;

Fig. 4 is an end view of the same.

50. Fig. 5 is a section on the line 5^a—5^a in Fig. 2;

Fig. 6 is a view similar to Fig. 2 but showing a modified form of construction.

55. Fig. 7 is a sectional view on the line 7^a—7^a in Fig. 6;

Fig. 8 is an enlarged side view of a modified form of tube means, and Fig. 9 is a view at right angles to Fig. 8.

Similar reference numerals throughout the several views indicate the same parts.

60. The invention is embodied in the present instance in combination with a form of container commonly employed for processing substances, comprising a substantially cylindrical open topped metal vessel having side walls 10. In the present instance the container is provided with jacket means comprising an outer spaced wall 11 which in one form of the embodiment is flanged inwardly at its top 12 and united with the container walls proper thus forming an annular chamber 13 about the container in which the temperature controlling fluid is circulated.

65. The fluid circulating means preferably comprises a conduit or pipe 14 arranged about the container adjacent its top. In the modification shown in Figs. 1 and 2, this conduit is constructed as a continuous ring having connections 15 leading to a suitable source of supply of fluid under pressure, and the conduit is carried on the flange 12 of the jacket by a series of oval nipples 16 which space and support the conduit and may be welded at one end to the latter and at the other to the jacket. The circulating fluid is transmitted from the conduit to the container wall through these nipples, to which end the conduit is provided, on the side thereof adjacent the container, with a slot 17, Figs. 2 and 5, within the dimensions of the bore of each nipple. The jacket flange 12, within the other end of each nipple, has a pair of openings 18 formed therethrough and a pair of relatively small distributing tubes 19 are removably inserted through each slot 17 and through the respective openings 18 in which they have a close, sliding fit. Tubes 19 extend at one end adjacent the center of conduit 14 and downwardly and inwardly at the other end into proximity with the outer surface of the container wall against which in the present instance these ends rest. Each tube preferably communicates with conduit 14 by a plurality of lateral openings 20 and 21. Thus the end of the tube may be somewhat contracted, as shown, with its extremity transversely grooved as at 20. This construction prevents the closure of the end of the tube by a flake of scale or other foreign matter, the later-

ally communicating grooves insuring continued communication with the tube under such circumstances and an equalization of pressure within and without the tube tending to prevent particles being held over the end of the tube by pressure differences. In addition other lateral openings 21 may be formed in the tube within the conduit and within the nipple 16 are located other lateral 10 openings 16^a with which the conduit communicates through slot 17. This construction insures continued free flow of fluid into the tube despite the presence of scale or dirt, it being noted that the open end of the tube 15 and the perforations 21 are located above the bottom of the conduit and of the nipple on which obstructing foreign matter tends to deposit.

The employment of the tubes 19 not only 20 has the advantage described above of avoiding obstruction of the passages but also the important result of accomplishing distribution of the fluid over the outer surface of the container wall in the most efficient manner. 25 The end of each tube being arranged as described in proximity with the container wall, the fluid flows in a continuous unbroken stream onto the wall as if through a bend at this point in the tube and is spread in a quiet 30 manner laterally over the wall at each tube without splashing or scattering, so that all of the fluid is effectively applied to the wall and distributed with substantial uniformity. An applied fluid pressure of two to five 35 pounds has been found advantageous but this may of course be varied to suit conditions. The tubes are so located and arranged that their ends have a substantially uniform spacing about the container such that the 40 vertical strip of film formed by each tube unites with the strips of adjacent tubes to form a film extending continuously about the container.

Conduit 14 is provided with openings 22, 45 one opposite each tube 19, or each adjacent pair of the latter, as shown in Fig. 5, affording access to the tubes for cleaning or removing the same when necessary, it being apparent that each tube may be quickly withdrawn longitudinally and removed through the adjacent opening 22 which latter is provided with a removable screw closure 23. For this purpose the tubes of each pair are 50 preferably inclined toward each other and the opening 22, as shown.

In Figs. 6 and 7 is shown a modified form 55 of construction in which the conduit 24 itself forms the connection between the container wall 25 and the jacket 26 by having its opposite sides welded as at 27 to these respective portions. The conduit is formed with openings 28 for tubes 29 inclined inwardly and downwardly as before with one end 30 located in the conduit above the bottom of the latter and preferably grooved to provide

lateral openings for the purpose described above. The other end of the tube extends as before into proximity with the container wall. The same construction of tubes may be employed in this modification but there is 70 shown in the drawings a tube having a modified inner end, which, instead of lying in a transverse plane preferably has opposite side portions drawn together as at 31 and cut away at the corners thus formed, as at 32, to provide a pair of laterally opposite openings 33 through which the fluid is discharged in unbroken streams directly onto the container wall. In this arrangement also the conduit 75 has opposite each tube an opening 34 for access to the latter, closed by a removable plug 35. The tubes may be arranged in the single manner shown in Fig. 7 or in pairs of inclined tubes as in Fig. 5 and obviously the tubes may be arranged singly instead of in 80 pairs in the construction of Fig. 5.

Figs. 8 and 9 illustrate a further modification of the distributing tube which in this form is flattened and closed as at 36 and the side portions thus brought together perforated at 37, to provide an eye with which a hook may be engaged for conveniently withdrawing the tube. In this construction, the tube is preferably formed with a plurality of lateral openings 38 having the advantages described above.

The construction of the distributing tubes with inlet openings of smaller area than the discharge opening adjacent the container walls materially assists in effectively discharging the liquid over the walls because of the reduction in pressure and velocity of the liquid at the discharge end of the tube which allows the liquid to flow quietly and smoothly into films on the container walls. 100 This advantage is obviously maintained by this construction in spite of variations in the pressure of the liquid as applied to the tube inlets, and permits of the application of a considerably higher pressure without a substantial interference with this effective distribution. Furthermore the maintenance in this manner of a substantial difference in pressure between the liquid supply pipe 14 and the interior of the tubes assists in preventing obstruction of the tube inlets.

As apparent from the above description and the drawings, the invention provides a simple form of construction which may be manufactured economically by practical 110 means and methods and the construction operates to distribute the circulating fluid in a highly efficient manner over the walls of the container so that all of the fluid is effectively used thus reducing the quantity 115 required. The invention furthermore provides a construction effectively safeguarding against clogging by foreign matter, while the fluid distributing parts are so constructed and arranged as to be easy of ac- 120 125 130

cess for cleaning or replacing when necessary.

I claim as my invention:

1. In apparatus of the character described, the combination with a container of a supply conduit for a temperature controlling medium provided with a multiplicity of independently mounted members removable through the conduit and located in proximity to the wall of the container for distributing said medium over said wall in the form of a fluid film.
2. In apparatus of the character described, the combination with a container of conducting means for a temperature controlling medium comprising a multiplicity of spaced tubes projecting into proximity with the container wall for distributing said medium over said wall in the form of an unbroken film.
3. In apparatus of the character described, the combination with a container of a conduit therefor for a temperature controlling medium and a multiplicity of spaced tubes communicating at one end with said conduit above the bottom thereof and extending at the other end into proximity with the container wall for distributing said medium over said wall in an unbroken film.
4. In apparatus of the character described, the combination with a container of a conduit arranged exteriorly about the container wall adjacent its top and a multiplicity of spaced tubes communicating at one end with said conduit above the bottom thereof and extending at the other end into proximity with the container wall for distributing a temperature controlling medium over said wall in an unbroken film.
5. In apparatus of the character described, the combination with a container of a conduit arranged exteriorly about the container wall adjacent its top and provided with spaced openings on the side thereof adjacent said wall, a multiplicity of tubes removably inserted through said openings with one end of each tube communicating with said conduit and the other end extending into proximity with the container wall for distributing a temperature controlling medium over said wall in an unbroken film, said conduit having openings therein provided with removable closures opposite said tubes for access thereto.
6. In apparatus of the character described, the combination with a container of a conduit arranged exteriorly about the container wall adjacent its top and having therein a series of spaced openings provided with removable closures affording access to the conduit interior, said conduit having therein also a series of additional openings on the side thereof adjacent the container wall and opposite said first openings, and a multiplicity of pairs of tubes removably inserted in said additional openings with one end of each tube communicating with said conduit and the other end extending into proximity with the container wall for distributing a temperature controlling medium thereover in an unbroken film, the tubes of each of said pairs being inclined toward one of said first openings in the conduit.
7. In apparatus of the character described, the combination with a container having a jacket enclosing a chamber about the container walls, of a conduit extending about the container adjacent the top of said jacket, and a multiplicity of spaced tubes communicating at one end with said conduit and extending at the other end into said chamber and into proximity with the container wall for distributing a temperature controlling medium thereover in a fluid unbroken film.
8. In apparatus of the character described, the combination with a container of a conduit therefor for a temperature controlling medium and a multiplicity of spaced tubes each having one end extending into said conduit and provided with a plurality of lateral openings and the other end extending into proximity with the container wall for distributing said medium thereover in a fluid film.
9. In apparatus of the character described, the combination with a container of a conduit therefor for a temperature controlling medium and a multiplicity of spaced tubes each having one end extending into said conduit and transversely grooved at the extremity thereof to provide a plurality of lateral openings and the other end extending into proximity with the container wall for distributing said medium thereover in a fluid film.
10. In apparatus of the character described, the combination with a container of a conduit therefor for a temperature controlling medium, a multiplicity of tubes removably inserted through openings in the conduit with one end of each tube extending into the conduit and provided with lateral openings and the other end extending into proximity with the container wall for distributing said medium thereover in a fluid film said tubes having a relative spacing adapted to unite the respective films thereof, said conduit having openings therein opposite said tubes for access thereto, and removable closures for said latter openings.

ELLIOTT E. GEISINGER.
